UNITED STATES PATENT OFFICE.

JULIUS PEGEL, OF PHILADELPHIA, PENNSYLVANIA, ASSIGNOR TO JOHN BROMLEY & SONS.

DESIGN FOR A TABLE-COVER, &c.

SPECIFICATION forming part of Design No. 20,180, dated September 30, 1890.

Application filed August 30, 1890. Serial No. 363,557. Term of patent 3½ years.

To all whom it may concern:

Be it known that I, JULIUS PEGEL, a subject of the Emperor of Germany, residing in the city of Philadelphia, State of Pennsylvania, 5 have invented and produced a new and original Design for a Table-Cover or Curtain, of which the following is a full, clear, and exact description, reference being had to the accompanying drawing, forming a part of this 10 specification.

My invention has relation to the surface ornamentation of woven textile fabrics, and is applicable more particularly as a bordering for a chenille table-cover or a curtain.

The nature and character of the design will 15 be fully understood by reference to the accompanying photographic illustration, hereto annexed and made a part of this specification.

I claim—

The design, substantially as shown and set 20 forth.

In testimony whereof I have hereunto affixed my signature this 31st day of July, A. D. 1890.

JULIUS PEGEL.
